UNITED STATES PATENT OFFICE.

S. F. VAN CHOATE, OF YREKA, CALIFORNIA.

IMPROVED MAGNETIC PRINTING-TELEGRAPH.

Specification forming part of Letters Patent No. 27,655, dated March 27, 1860.

To all whom it may concern:

Be it known that I, S. F. VAN CHOATE, of Yreka, in the county of Siskiyou and State of California, have invented certain new and useful Improvements in Magnetic Printing-Telegraphs; and I do hereby declare that the following is a full, clear, and exact description of the same, reference being had to the accompanying drawings, forming part of this specification, in which—

Figure 1 is a front view of my composing and printing instrument, exhibiting part of the printing apparatus in section. Fig. 2 is a back view of the same. Fig. 3 is a vertical section of the same, taken at right angles to Figs. 1 and 2. Fig. 4 is a vertical section of the same, taken in a plane parallel with Figs. 1 and 2. Fig. 5 is a plan of the base and key-board of the instrument. Figs. 6, 7, 8, and 9 are views exhibiting some of the details of the machine. Fig. 10 is a diagram giving a general view of the circuits.

Similar letters of reference indicate corresponding parts in the several figures.

My invention consists in certain improvements in magnetic-telegraph instruments, whereby I reduce very materially the amount of magnetic force necessary to effect their operation, and am enabled to operate effectively with a battery of no great power and without the use of relays or local batteries.

To enable others skilled in the art to make and use my invention, I will proceed to describe its construction and operation.

A A are two parallel upright plates, of metal or other material, erected upon a wooden base, B, and stayed together by stretchers A' A', to make a stiff framing to hold the working parts of the instrument.

C, Figs. 1 and 2, is the type-wheel by which the printing is effected, which carries the types a a, representing the letters of the alphabet, with such signs or numbers as it may be desired to use, said types being arranged at equal distances apart on the circumference of the wheel, and a space, b, being left at one point of the circumference of a width equal to one tooth and two of the other spaces between the teeth, such space being for the purpose of making the necessary spaces between the words in printing. In speaking of the number of types

on this wheel throughout this specification I wish to be understood as including also the space b. The said type-wheel is made fast on a horizontal shaft, c, which works in bearings in the two side frames, A, and which is geared by a train of wheel-work, d e f f' g g' h i j j' k, with a drum or barrel, D; to which motive power is applied by a spring or weight in such manner as to produce a rotary movement of the said wheel under the control of an escapement, whose operation is governed by two upright electro-magnets, E F, and a horizontal permanent steel magnet, G, of horseshoe form, in a manner to be presently described. The escape-wheel H of the said escapement has a number of teeth corresponding with the number of types on the type-wheel, and is fast on a shaft, l, which is arranged parallel with the type-wheel shaft c in bearings in the plates A A, and which is geared with the type-wheel shaft by two gears, n o, having each the same number of teeth.

The anchor I is attached to a rock-shaft, p, fitted to work in bearings in the plates A A, and is slotted to receive a pin, r, attached to the lower arm of a cruciform lever, J', to opposite arms of which, at equal distances from the center or fulcrum q, are attached the armatures E' F' of the two upright electro-magnets E F, as shown in Fig. 4. This lever is attached to a rock-shaft, q, which works in bearings in the plates A A. The upper arm of the said lever passes through the upper stretcher, A', of the framing, in which there may be fitted set-screws to control its movement in such manner as to prevent the armatures from ever actually touching the poles of their respective electro-magnets, but to permit them to approach very near the said poles.

The electro-magnet E is secured to the framing by a bar, E*, of insulating material, which insulates it from every part of the instrument; but the electro-magnet F has the central soft-iron cores of its two helices screwed into or otherwise secured in the two arms of the horizontally-arranged permanent magnet G, which is secured to the framing by a bar, G*, of insulating material.

The helices of the two electro-magnets E F are connected together in such manner that both of said magnets are in the same electric

circuit, and the arrangement of the helices of the magnet F with respect to the battery or other generator of electricity by which the line is to be worked, and in the circuit of which the said magnets are placed, is such that a positive pole of the said electro-magnet may meet the positive pole of the said permanent magnet and a negative pole of the said electro-magnet may meet the negative pole of the said permanent magnet, the effect of which arrangement of the poles is that when a current of electricity passes through the helix of said electro-magnet it simply has the effect of neutralizing the magnetism of the permanent magnet and preventing the latter from attracting the armature F', as it does when no electricity passes through the helices of F. By thus combining the electro-magnet F and permanent magnet G and applying them in relation to the electro-magnet E, the cruciform double armature-lever I, and the anchor of the escapement, I am enabled to obtain the necessary motion of the anchor to permit the escape-wheel to move tooth by tooth by opening and closing the circuit through the helices of the two electro-magnets, or, in other words, by alternately bringing the said helices into and cutting them out from an electric circuit, for when the circuit is closed through the helices the magnet E attracts its armature E', and when no electricity passes through the helices the armature F' is attracted by the magnet G. In this way the escapement is enabled to be worked with a very slight battery-power, for the armatures are arranged to balance each other, and the springs commonly applied to the armatures of electro-magnets employed in telegraph-instruments are dispensed with, and therefore no battery-power is wasted in overcoming the tension of such springs.

The electro-magnet F may have its central soft-iron cores solid and applied in the usual manner; but it is greatly preferable to construct and apply the cores in the manner represented in Fig. 9, and described as follows: The figure represents a central section of one of the spool-like portions of the magnet. The core is composed of two pieces, 69 and 70. The piece 69 consists of a cylindrical soft-iron tube, to the lower end of which is secured the lower insulated flange, 71, of the spool, and near the upper end of which is screwed the upper insulated flange, 72, leaving a part projecting through the said upper flange, and on the exterior of the part so projecting is cut a screw-thread, onto which is screwed a flat piece of soft iron, 73, which lies flat upon the top of the insulated flange 72. The central piece, 70, of the core, which is also of soft iron, is made solid and fitted to the interior of the tubular piece 69, so that the latter may slip over it, and this solid central piece, which is screwed or otherwise secured into one of the arms of the permanent steel magnet G, is made of such length that when the tubular portion is slipped over it its top is flush with the top of the tu-

bular portion and the piece 73. The object of this construction of the core is as follows: When the electrical current passes into the electro-magnet it neutralizes the influence that the permanent magnet has over the soft-iron cores, and if the cores of the electro-helices were solid and attached to the permanent magnet the action of the current upon the electro-magnet would effect this neutralization so completely that when the circuit of the electro-magnets was opened the permanent magnet would regain its natural attractive state very slowly; but by constructing the cores as I have above described the outside tubular core, 69, is totally neutralize, but the inside core only partially so, and hence the permanent magnet is enabled to quickly restore the attractive power to the outside core, which is attached to the piece 73 of soft iron, the object of which is to increase the attractive surface presented to the armature. This construction of the electro-magnet F also allows it to be taken apart easily.

J, Figs. 3, 6, and 7, is what I call the "intermitting-wheel," secured to the opposite end of the type-wheel shaft to that at which the latter wheel is secured. This intermitting-wheel is made in two pieces—viz., one of brass or other metal and the other of some insulating material, as illustrated by Figs. 6 and 7, the latter representing an inside face view of one of the pieces and the former exhibiting a central section of the wheel complete on a larger scale than the other figures. Each of these pieces consists of a disk with a number of teeth, s s, equal to the number of types on the type-wheel, such teeth projecting both in a radial direction, as shown in Fig. 7, and from one side, as shown in Fig. 6, the spaces between said teeth being of the same width and shape as the teeth themselves, so that when the two pieces are placed together the teeth on one may enter the spaces between the teeth of the other, as shown in Fig. 6, so that the two combine to form a solid disk or wheel, which presents on its periphery a narrow surface of metal and a narrow surface of insulating material alternately all the way round. The metal portion of this wheel is tinted yellow and the portion made of non-conducting or insulating material tinted gray in the drawings. The said wheel is secured to the type-wheel shaft in such manner that its metallic portion is insulated from the said shaft. c', Figs. 2 and 6, is a short shaft of metal, forming a continuation of the shaft c outside of the intermitting-wheel, said shaft c' being secured to the latter wheel and being in contact with its metallic portion, but insulated from c by the non-conducting portion of the intermitting wheel, as shown in Fig. 6.

u, Figs. 2 and 3, is a wire spring or brake, held in such manner as to press against the end of the shaft c' by a stationary metal screw cup or stud, u', which is attached to the insulated check-plate K, hereinafter described, but which might be attached to any other stationary

part of the instrument with proper insulation. v is a wire spring or brake, held in such manner that its point presses upon the periphery of the intermitting-wheel by means of a stationary screw-cup, v' , which is secured to but insulated from the framing of the instrument.

The screw-cup v' of the brake v is connected by a wire, 12, with one end of the main wire M M' at the station where the instrument is placed, and the screw-cup w' of the brake w is connected by wires 13 and 20 with one extremity of the coil of the magnet E, the other end of which being connected with one end of the coil of the magnet F, whose opposite end is connected by a wire, 14, with the other end of the line-wire. By this system of connections, when the circuit of the main line is completed through the brakes v , wheel J, shaft c' , and brake u , the brake v resting upon one of the metal teeth of the intermitting-wheel, the electro-magnet E being charged, and thereby rendered active, and the permanent magnet G being polarized by the magnet F, and thereby rendered inactive, the armature E' is drawn down and the escapement-wheel allowed to move one tooth, which brings the insulated spaces of the wheel J into contact with the brake v , and so opens the circuit and renders the magnet E inactive and G active, so that the armature F' is attracted and the escapement-wheel allowed to move another tooth, which brings another metal tooth of the wheel J into contact with the brake v and closes the circuit again. In this way a rapid intermittent movement of the intermitting-wheel J and the type-wheel is obtained, and the breaking and closing of the circuit by means of the said wheel J will cause the armatures of any number of similar instruments arranged in the same telegraph line or circuit to be similarly operated, and hence, if the type-wheels of the several instruments are adjusted to bring their types to similar positions, the same relation will be preserved throughout them all by the intermitting-wheel of any instrument on the line that may be employed in sending messages.

The shaft c' , above described, has attached to it what may be termed a "sweep," t , (see Figs. 2, 3, and 4,) consisting of a radial arm having a cylindrical hub, t' , which is secured firmly to the shaft c' , but insulated therefrom by an interposed bushing, t'' , of insulating material. This sweep carries a wire spring or brake, t'' , the point of which bears upon the peripheral surface of what I call the "check-plate," K, the duty of which is to effect the stoppage of the type-wheel with that type which is requisite to print in the proper position for printing. This check-plate is the exact counterpart of the intermitting-wheel J, except that it has a central opening large enough for the hub t' of the sweep t to pass through it without touching it. It is stationary outside of the intermitting-wheel and sweep, not far from and concentric with the intermitting-wheel, in which position it is supported by a bracket, L, of insulating material, secured to one of the plates A A of the framing.

To the outer face of the check-plate which belongs to the part composed of insulating material there is secured a screw-cup, w' , which holds a wire spring or brake, w , in such a manner as to keep it always pressing upon the periphery of the hub t' of the sweep, and to the same screw-cup w' is attached the end of a wire, 15, which forms part of a different branch of the circuit to that which passes through the brakes u and intermitting-wheel.

The screw-cup w' is not of necessity secured to the check-plate, but only as a matter of convenience, for it may be secured to any other stationary portion of the framing if properly insulated therefrom.

From every one of the metal teeth $s' s''$ of the check-plate a wire, 16, leads down through a hole, x , in the base to a separate one of a corresponding number of metal springs, N N, arranged below the hollow wooden base B and secured to the back part thereof, as shown in Figs. 3 and 5; but to prevent confusion of parts in the drawings only one of these wires and a few of the springs are represented. The said springs are arranged one over the rear end of each of the brass keys O O, of which the number corresponds with the number of types in the type-wheel. The keys resemble those of a piano-forte, and they project from under the front part of the wooden base. All work upon a long pin, y , which passes through a series of lugs formed upon a plate, y' , which is secured to the base. Each one has a spring, y'' , applied in such a manner as to press the rear portion downward, and by the action of these springs y'' they are all kept clear of their respective springs N N until their front ends are depressed by the operator.

Between the keys and the top of the cavity of the base, and near the middle of the row of keys, there is arranged a small brass lever, z , which is fitted to work on a fulcrum, z' , supported in the lugs of a brass plate, z'' , that is secured to the base B. The rear arm of this lever is furnished with a rigidly-connected cross-piece, z'' , (dotted in Fig. 5,) which extends across the whole series of keys, and a spring, z'' , is applied to the said arm of the said lever in such a manner as to force the said cross-piece downward toward the keys, and force the front arm of the said lever upward toward the point of a brass screw, P, which is secured into a brass plate, P', on the top of the base, and which passes through the base. When the keys are all at rest the spring z'' holds the lever z in contact with the screw P, and with its cross-piece z'' resting on all the keys; but when any key is depressed by the operator its rear portion presses upward the cross-piece z'' , and so breaks the contact between the lever z and the screw P; but the springs N N and the lever z are so arranged relatively to each other that the key does not break the contact between the lever z and screw P till it has arrived in contact with its respective spring N. The lever z is made to form a portion of two separate branch

circuits—viz., one through the wire 15 and another through the wire 13—as will be presently described, by means of the screw P, plate P', a wire, 17, connecting the said plate P' with the said wires 13 and 15, and a wire, 18, which passes through an opening, z' , in the base and connects the plate z^2 with the main wire. Each key is made to form part of one of a number of separate branch circuits, of which one of the wires 16 and one of the metal teeth s' of the check-plate form parts, by means of a wire, 19, which passes through a hole, z^2 , in the base and connects the plate y' with the main wire.

Having now described the construction and arrangement of all those parts of the instrument by which the operations of its type-wheel and of the type-wheels of the other instruments along the line are controlled, I will proceed to complete the description of the operation of those parts before describing the printing apparatus, as by that course the latter may be more easily explained.

I will first suppose all the instruments of the line to be at rest, in which case the circuit is closed throughout, and the current, entering the instrument at M, passes along the wire 18, through the base to the plate z' , through the said plate, pin z' , lever z , screw P, plate P', wires 17 and 20—such parts constituting the short branch circuit 1* of Fig. 10—through the helices of both electro-magnets E F, and from the latter along the wire 14 to the end M' of the main line, without passing through the key, the intermitting-wheel, or the check-plate, the branch-circuit 3* of Fig. 10, in which the intermitting-wheel is placed, being open in consequence of the instrument always stopping with the brake v resting on one of the insulated spaces of said wheel, and the branch 2* of Fig. 10, in which the check-plate is placed, being open at the key. In this condition the armature E' is attracted by the magnet E; but when a key is depressed by the operator at any station the circuit is opened at the point of the screw P by the upward pressure of the key upon the cross-piece z^3 of the lever z , which forces the said lever out of contact with the screw, and the magnet G, then becoming active, attracts the armature F', and so by the action of its lever J' on the anchor permits the escape-wheel H to move one tooth and bring a brass tooth of the intermitting-wheel into contact with the brake, and thus close the circuit. The current now passes from M through the wire 12, screw-cup v' , brake v , intermitting-wheel J, shaft c' , brake u , cup u' , wires 13 and 20—which parts constitute the branch circuit 3* of Fig. 10—through the helices of both electro-magnets E F and wire 14 to M'; but no sooner is this the case than the armature E', becoming attracted, permits the escape-wheel H to move another tooth, which causes the intermitting-wheel to present another insulated space to the brake v . This opening and closing of the circuit produces a rapid intermittent movement of the type-

wheel of the instrument whose key is depressed, and, as hereinbefore explained, a corresponding movement of all the instruments along the line, which continues until the sweep t , in its revolution with the type-wheel and intermitting-wheel, brings its brake t^3 into contact with that tooth s' of the check-wheel which is connected with the spring N belonging to the depressed key, (by wire 16,) when the current finds a shorter circuit than that through the intermitting-wheel and wire 13, the latter being coiled, as shown in Figs. 2 and 3 to make a longer circuit—viz., from M through wire 19, Fig. 3, to key-plate y' , thence through pin y and depressed key, through spring N of said key, along wire 16 to tooth of check-plate, through brake t^3 , sweep t , brake w , cup w' , wires 15 and 20—which parts constitute the branch 2* of Fig. 10 of the circuit—through helices of magnets E F, and from thence, owing to the closing of the printing-circuit, (not yet described,) is shorter than the wire 14, it passes over the said circuit to M', and as the circuit is now permanently closed, the intermitting-wheel being out of circuit, the instrument stops, with the armature E' attracted by the magnet E and the type-wheel with the type corresponding with the depressed key opposite the printing-roller S, and all the other instruments in the same line stop with their type-wheels in the same position, and will remain so after the key has been permitted to rise until another key is depressed or the same depressed again, for as the front of the key rises the rear portion does not move out of contact with the spring N till after the circuit has been closed at the point of the screw P, and the current takes the short branch 1* of the circuit, which it has been before described as taking when the instrument is at rest. It is proper to add, however, that it is unnecessary for the key to leave the spring N at all, as the short branch 1* of the circuit is shorter than that through the key, and in fact the shortest of all the branches, and of course the current prefers the shortest circuit, and it is upon this action of electrical currents that the instrument depends in a great degree for its operation, the key being used to change the circuit from one to another of three branches of the same main circuit.

I will now proceed to describe the printing apparatus.

S is the printing-roller, between which and the type-wheel the strip of paper 23 (represented by a blue line in Fig. 1) on which the message is to be printed passes to receive the impressions of the types, such roller having its periphery covered with some suitable elastic or yielding material, and being arranged below the type-wheel in a frame, S', which is fitted to slide in vertical guides 21, attached to one of the plates A A. This frame S' is fitted with a yoke, S², which is acted upon to raise the said frame and press the printing-roller upward against the type-wheel to produce the impression every time the type-wheel

stops by means of a wiper-wheel, T, on a horizontal shaft, 22, which works in bearings in the two plates A A. This shaft is always locked, except at the instant the type-wheel stops after having operated, as hereinbefore described, to present the desired type opposite the printing-cylinder, when it is unlocked and allowed to make very suddenly a sufficient portion of a revolution to enable one of the wipers of the wheel T to raise the frame S' and printing-roller S, and let them descend again, such movement being effected by means of a spring or weight applied to a drum or barrel, U, which is geared with the said shaft by means of a cog-wheel, 24, on the said drum, and a pinion, 25, on the said shaft.

The printing-roller is furnished near each end with a series of sharp teeth, which serve to feed the strip of paper to the type-wheel, the paper being held against the said teeth by a forked spring, 26, attached to the frame S', and the necessary movement on the roller to effect the feed being produced by means of a ratchet-wheel, 27, which is fast on the end of the roller, and a spring-dog, 28, which is attached to one of the plates A A in such a position that every time the frame S' descends with the roller after having produced an impression a tooth of the ratchet-wheel is operated upon by the said dog. The wiper-wheel T only raises the frame S' to produce the impression, and it (the said frame S') is pulled down again after having made the impression by a spring, 29, connecting it with a bracket, 30, attached to the plate A, such connection being made by means of a screw and nut, 31, which allows the force of said spring to be adjusted.

To provide for the adjustment of the printing-roller to give the requisite pressure to produce the impression, the yoke S² is fitted to slide vertically in the frame S', and has a screw, 32, applied in such a manner as to be capable of raising or lowering it.

The types may be kept inked by their revolution in contact with a stationary brush, C', (see Fig. 1,) which is kept constantly supplied with ink from a funnel, C²; or the paper, if prepared with proper chemical agents, may be printed by making the type-wheel and printing-roller constitute portions of a branch of the printing-circuit and closing such branch by means of the paper when the printing-roller is raised.

The mechanism by which the unlocking and locking of the shaft 22 are effected, which will be presently described, is controlled by the combination of permanent magnet V and an electro-magnet, W, of precisely similar description to the magnets G and F, the permanent magnet V lying flat upon the base B, and being secured to the frame A A, and the cores of the two helices of the magnet W being arranged vertically and secured to the ends with the positive pole of one core in contact with the positive pole of the permanent magnet

and the negative pole of the other core next the negative pole of the permanent magnet.

The helices of the magnet W are in the branch of the circuit which I call the "printing-circuit," (marked 4* in Fig. 10,) which is entirely distinct from any of the branches hereinbefore described, as shown by Fig. 10. This branch of the circuit is formed in the following manner: One extremity of the coils of said helices is connected by a wire, 33, passing through an insulator, 34, Fig. 2, in the framing, with a brass screw-plate, 35, Fig. 4, which is attached to a stationary bar, 40, of insulating material, arranged between the plates A. This screw-plate 35 receives a screw, 36, the point of which serves as a resting-place for the lower part of a bent lever, 41, which constitutes part of what I call the "circuit-breaker," and which is arranged to vibrate freely on a pin, 37, in a small brass standard, 38, erected upon the bar 40. The standard 38 is connected by a wire, 39, passing through the insulator 34 to the outside of the framing up to that extremity of the coils of the magnet F which connects with the wire 14, as shown in Fig. 2. The other extremity of the coils of the helices W connects with the main line at M'.

The wire 14, it will be observed by reference to Figs. 2 and 3, is made with a coil, and the length of the part of circuit formed by this coil should be greater than the whole length of the printing-circuit, so that when the latter is closed by the contact of the lever 41 with the point of the screw 36 the current passes through it in preference to the wire 14. This printing-circuit is closed when the instrument is at rest; but when the key is first depressed and the type-wheel and intermitting-wheel set in motion the printing-circuit is opened at the point of the screw 36 by the action of a ratchet-like wheel, 42, Figs. 3 and 4, which constitutes the other portion of the circuit-breaker, and is carried by the type-wheel shaft e upon the pawl-like upper extremity of the lever 41. This wheel 42 has a number of ratchet-like teeth equal to the number of types on the type-wheel, and while the type-wheel shaft and intermitter are moving to bring the type-wheel to the position to print, after the depression of the key, the teeth of the said ratchet-wheel pass the lever 41 so quickly as to prevent its contact with the point of the screw 36, keeping it, as it were, dancing upon them; but the slightest perceptible stoppage or hesitation (if such an expression may be used) of the wheel 42 of the circuit-breaker permits the lever to come in contact with the screw and close the printing-circuit, and hence such circuit is closed the instant the type-wheel is stopped by the check-plate K coming into circuit with the key, as before described. It is the closing of this circuit which causes the unlocking of the wiper-wheel shaft 22, before described, and permits it to be operated by the drum U to raise the printing-roller.

The locking and unlocking mechanism, which I am now about to describe, is operated upon by the armature W' of the combined permanent and electro magnets. This armature, which is faced with brass, as shown in Fig. 4 in the drawings, to prevent its adhesion to the poles of the magnet W , is attached to a forked lever, X , which is arranged to work on a stationary fulcrum, 43, and the said lever has applied to it a spring, 44, which tends to draw it away from the magnet W , when, by the closing of the circuit through the helices thereof, the attraction of the armature is caused to cease. The said spring is allowed to draw up the armature a considerable distance, which may be regulated by a stop-screw, 45, screwed through a bridge-piece, 46, placed across the framing.

The extremity of the armature-lever X , which is a beveled upward projection, 47, on its upper surface, as shown in Fig. 4, is situated in a plane a short distance horizontally from the plane of one face of a small wheel or disk, Y , which is fast upon a shaft, 48, which is arranged parallel with the wiper-wheel shaft 25 and other shafts of the instrument in suitable bearings, and is geared with the said shaft 25 by a wheel, 56, and pinion 57 in such a manner that it will make a complete revolution during the portion of a revolution of the wiper-wheel shaft occupied by the action of one of its wipers. For instance, the wiper-wheel represented has four wipers, and the shaft 48 makes one revolution for one-quarter revolution of the shaft 25. The said wheel Y , which, besides being represented in Figs. 3 and 4, is represented detached on a larger scale in Fig. 8, consists of a circular disk concentric to its shaft, and having in its periphery a single notch, 49, to receive a stop-pawl, 50, Fig. 4, which forms part of a bent lever, Z , which is secured to a small horizontal rock-shaft, 51, which works freely in bearings in the framing, said pawl serving to prevent the revolution of the wheel Y and its shaft 48, and consequently that of the wiper-wheel shaft.

On that side of the wheel Y on which the projection 47 of the armature-lever is situated there is a small sliding bolt, 52, fitted to work parallel with the side of the said wheel in guides 53 provided thereon, and having a spring, 54, coiled round it, and so applied as to draw its head just within the bottom of the notch 49, so that it is just clear of the pawl 50 when the notch receives the latter, in which condition of the wheel the bolt is in the upright position shown in Figs. 4 and 8, and its lower extremity is situated above the point of an upright screw, 55, which is screwed into the armature-lever on one side of the beveled projection 47.

When there is no electricity in the coils W , which is the case during the action of the intermitting-wheel, the armature W' is held down by the attraction of the magnet V and the wheel Y remains locked by the pawl 50; but as soon as the closing of the circuit through

those helices takes place and the magnet V is rendered inactive the armature-lever is drawn up by the spring 44 and the screw 55 pushes up the bolt 52 against the pawl 50 and lifts the latter out of the notch 49. The wheel Y , being thus unlocked, is allowed to make one revolution, which is performed with great rapidity, and thus allows the wiper-wheel shaft 22 to make the required portion of a revolution to operate the printing-roller. As the wheel Y completes its revolution a small cam, 56, attached to the said wheel by a pin, 57, comes into operation on the beveled projection 47 on the top of the armature-lever, and so depresses the said lever far enough to prevent its screw 55 from catching the lower end of the bolt 52, which, being left under the influence of its spring 54, permits the pawl 50 to drop into the notch again and stop the wheel; but the said cam does not depress the armature-lever as far as it is capable of moving toward the magnet V , but far enough to bring the armature very near the poles of said magnet. The said cam 56 is so applied as to be free to work a little way on the pin 57; but its movement thereon is limited by two stoppins, 58 and 59, (see Fig. 8,) attached to the wheel, and a spring, 60, is applied to it in such a manner as to press it toward the pin 58. As the said cam comes into action on the bevel 47 of the armature-lever it is forced by the friction upon said lever away from the stoppin 58 and into contact with the stop-pin 59, and so remains after the key is allowed to rise and until by the depression of another key or by the same key being again depressed the type wheel and check-wheel and the wheel 42 of the circuit-breaker are set in operation, when the latter opens the printing-circuit, and the armature W' is thus caused to be attracted by the magnet V . The further descent of the lever X with the armature takes it clear of the point of the cam 56 and allows the spring to move the latter back to the stop-pin 58, thus throwing the point of the cam over the highest part or heel of the beveled projection 47 of the lever, so that on the liberation of the armature by the closing of the printing-circuit the said cam may cause no obstruction to the rise of the lever X and consequent disengagement of the pawl 50. To prevent the pawl 50 being caused to jump out of the notch 49 by the sudden stoppage of the wheel Y , there is attached to the cam 56 a small sliding bolt, 61, which works through a guide, 62, attached to one side of the wheel, and which, as the cam 56 depresses the lever Y , is brought over the point of the turned up lower arm of the lever Z in such a manner that the said lever is caused to be positively locked with its pawl 50 in the notch 49 until by the further descent of the armature-lever the cam 56 is released and allowed, by its slipping over the projection 47, to remove the said bolt 61 out of the way of the lever Z , and so unlock the latter. Fig. 8 exhibits the lever Z as locked, the armature

W' not yet having been attracted by the magnet V, and Fig. 4 represents the armature as having been attracted and the lever Z unlocked and ready to be operated upon by the bolt 52 when the armature W' is liberated.

I have already explained how the synchronous operation of the type-wheels all along the line is effected by the operation of the intermitting-wheel of any instrument whose key is depressed, and as I have shown that the printing apparatus is unlocked and allowed to come into operation so soon as any stoppage or hesitation occurs in the movement of the type-wheel shaft by the circuit-breaker 42 allowing the lever 44 to come into contact with the screw 36, and thereby closing the printing-circuit, and so neutralizing the magnetism of the permanent magnet V, and hence, as all the circuit-breakers have the same operation throughout the line, it is obvious that the same operation of the printing apparatus takes place in every instrument. To explain the relation between the printing-circuit and the other circuits, I have given the diagram Fig. 10, where 1* represents the short branch of the circuit, through which the current passes when all the instruments are at rest. 3* represents the branch in which the shaft c', the intermitting-wheel, and the brakes v and u are placed. 2* represents one of the shorter branches, of which a key and the check-plate form parts. 4* represents the printing-circuit, and 14 represents the wire with the long coil, (indicated by the same letter in the other figures.) The short branch circuit 1* is never broken at any instrument but that from which the message is sent.

To enable the operator at any station to call the attention of operators at other stations, I propose to attach to each instrument a bell, 63, and a hammer, 64, attached to an elastic arm, 65, so arranged that it may be operated upon by a pin, 66, in the back of the type-wheel once in every revolution of the said wheel, to make the hammer strike the bell.

The hammer may be thrown out of operation at all times (but when the operator wishes to leave his instrument temporarily while no message is being received) by means of a cam, 67, attached by a stud, 68, to the framing of the instrument.

Having thus described my invention, I will proceed to state that what I claim as new, and desire to secure by Letters Patent, is—

1. The employment, in combination with the escapement which controls the operation of the

mechanism which drives the type-wheel, of two electro-magnets, E F, arranged in the same circuit, a permanent magnet, G, combined with one of such electro-magnets, as described, and two armatures, E' F', attached to a lever so applied relatively to the said magnets and escapement as to be operated, substantially as herein described, to control the escapement by the opening and closing of the main or through current of a line of telegraph.

2. The employment, in combination with the electro-magnet W of the printing-circuit and the permanent magnet V that is combined therewith, of a circuit-breaker composed of a ratchet-toothed wheel, 42, and lever 41, or their equivalents, applied and operating, substantially as herein described, to cause the opening of the printing-circuit while the type-wheel is in motion and the closing of the said circuit on the stoppage of the type-wheel, substantially as herein described.

3. Combining the lever which carries the armature of the printing-magnet with the printing mechanism by means of a notched wheel, Y, sliding bolt 52, cam 56, and spring 60, attached to said wheel, and a stop-pawl, 50, or their equivalents, the whole applied and operating, substantially as herein described, to cause the unlocking of the mechanism which brings the printing-roller into operation on the stoppage of the type-wheel and the relocking of the said mechanism after the printing operation.

4. The employment, in combination with each other and with three separate branches of the same main circuit, of a key, O, an intermitting-wheel, J, a check-plate, K, and a system of magnets, E F G, the whole operating together, substantially as herein described, for producing the synchronous operation of all the type-wheels on a line of telegraph and effecting the stoppage thereof in a position to present to their respective printing apparatus the letter corresponding with the depressed key.

5. In combination with the key, intermitting-wheel, check-plate, and system of magnets, and the three separate branches of a main circuit, as above described, the printing-circuit, circuit-breaker, and the branch circuit longer than the printing-circuit formed by the coiled wire 14, or its equivalent, the whole operating as and for the purpose herein specified.
